ABSTRACT

The output shaft of a starting mechanism is translatable by the magnetic flux of an energized actuator coil located about the shaft. The return path for this magnetic flux includes a cylinder affixed to the housing of the mechanism, an armature rotatable relative to both the shaft and housing, and a tachometer wheel driven by the shaft. The cylinder has one set of flanges that coact with a magnetic flux to pivot the armature and another set to coact with the tachometer wheel to induce a voltage in a tachometer coil as a result in changes in magnetic field through the cylinder. A pinion on the output shaft drives an idler gear that is pivoted into engagement with the starter gear of an internal combustion engine by a bracket connected to the actuator armature by a leaf spring. The actuator armature is also connected to the field switch for the starting motor by a linkage that closes the switch to start the motor when the magnetic flux aligns the armature with the flanges of the cylinder. Above a predetermined speed, a frequency detection circuit connected with the tachometer coil opens the current path through the actuator coil. When the actuator coil subsequently deenergizes, a return spring pivots the armature out of alignment with the flanges to disengage the starter gear and open the field switch.

STARTING MECHANISM

This invention relates to a starting mechanism of the type employing the magnetic field created by the energization of a single actuator coil to perform a plurality of functions.

The magnetic flux created by the energization of an actuator coil has heretofore been employed in starting mechanisms to translate its output shaft for the purpose of clutching a rotor, for engaging the starter gear of an internal combustion engine, or for controlling the field switch of the starting motor. In other starting mechanisms, magnetic action has been employed to rotate an idler gear driven by the output shaft into engagement with the starter gear. Moreover, it has been the normal practice with such magnetic action starting mechanisms to start up and shut down the starting motor by the manual control of the ignition switch.

The starting mechanism of the present invention provides all of these functions through the energization of a single actuator coil and the output provided by a tachometer coil, both such coils being wound concentrically about the output shaft of the mechanism. When energized through operation of the ignition switch of the vehicle, the actuator coil creates in the output shaft a magnetic flux of sufficient magnetomotive force to lift the rotor of the motor off a brake washer against the action of a helical restraining spring. The return path for the flux created by the actuator coil includes a tachometer wheel affixed to the shaft, an actuator cylinder supported by the housing of the mechanism, and an actuator armature pivotable relative to both the shaft and the cylinder between two positions. To cause rotation of the tachometer wheel to induce a voltage in the tachometer coil, a pair of diametrically opposed flanges extend axially from one end of the cylinder over the teeth of the tachometer wheel. To magnetically align the actuator armature in one of the two positions, a second pair of diametrically opposed flanges extend from the other end of the cylinder over the actuator armature. The output shaft of the mechanism is meshed with an idler gear that is pivotable into engagement with the starter gear by a leaf spring connecting the actuator armature with a bracket supporting the idler gear. When the idler gear is engaged with the starter gear, a linkage also connected to the actuator armature, closes the contacts of the field switch for the starting motor to commence rotation of the output shaft. When the shaft attains a predetermined speed, a circuit connected with the tachometer coil opens the current path through the actuator coil and allows the actuator to be energized. As the magnetic flux falls, the spring restraining the translation of the rotor slows down the rotor by urging it against the brake washer, and a second spring pivots the actuator armature out of alignment with the flanges of the actuator cylinder, thereby pivoting the idler gear out of engagement with the starter gear and also opening the field switch to the motor.

It is therefore a primary object of the present invention to provide a starting mechanism employing magnetic action to control both the engagement of an idler gear with the starter gear of an internal combustion engine and to control the application of current to the field of a starting motor.

It is a further object of the present invention to provide a starting mechanism wherein the magnetic field

provided by a first coil is employed to control the application of current to the field of the starting motor and also to induce in a second coil an AC signal, the frequency of which is used to control the energization of the first coil.

A first object of the present invention is to provide a starting mechanism wherein magnetic action created by the energization of a first coil controls the braking of the rotor of a starting motor and is interrupted by a tachometer wheel to induce voltages in a second coil adapted to be connected with a circuit for detecting the speed of the rotor.

It is a further and more specific object of the present invention to provide a starting mechanism of the foregoing type wherein the magnetic flux provided by the single actuator coil is employed to brake the rotor of a starting motor, pivot an idler gear on the output shaft of the mechanism into engagement with a starter gear of an internal combustion engine, and to operate a circuit for deenergizing the coil above a predetermined speed of the shaft.

These and other objects, advantages, and details of the present invention will become apparent with reference to the following description taken in conjunction with the drawings wherein:

FIG. 1 is a longitudinal view with parts in section of a starting mechanism constructed in accordance with the subject invention;

FIG. 2 is a view taken along line 2—2 in FIG. 1;

FIG. 3 is a view taken along line 3—3 in FIG. 1; and,

FIG. 4 is a circuit controlling the energization of the field and actuator coils of FIG. 1.

With reference now to FIG. 1, there is shown a starting motor 10 having a rotor 12 translated by the magnetic action of an actuator coil 14 to overcome the effect of spring 16 urging rotor 12 against brake washer 18. Rotor 12 has an output shaft 20 that is drivably connected to a pinion 22 rotatably supported in mesh with an idler gear 24 by an idler housing 26. This housing is pivotable about a hub 28 to swing idler gear 24 clockwise when viewed in FIG. 3 into engagement with the starting gear 30 of an internal combustion engine.

The return path for the magnetic flux created by the energization of actuator coil 14 includes a tachometer wheel 32 energization of actuator coil 14 includes a tachometer wheel 32 affixed to shaft 20, an actuator cylinder 34 press-fitted into housing 36, and an actuator armature 38 pivotable on the sleeve bearing 40 relative to both shaft 20 and cylinder 34. To effect such rotation, actuator armature 38 has a pair of diametrically opposed teeth 41 and 42 alignable by the magnetic action of actuator coil 14 under flanges 43 and 44 extending axially from one end of cylinder 34. When actuator coil 14 is deenergized, the teeth 41 and 42 of armature 38 are maintained in a nonaligned position relative to flanges 43 and 44 of cylinder 34 by a return spring 46, one end of which 47 is connected to armature 38 and the other end 48 of which is connected to cylinder 34. To allow idler gear 24 to be pivoted into engagement with starter gear 30, idler housing 26 has an opening (not shown) spanning the width of pinion 24 and is connected to actuator armature 38 by a leaf spring 50 through opening 52 of housing 36.

In addition to effecting such gear engagement, the alignment of the teeth 41 and 42 with flanges 43 and 44

upon the energization of actuator coil 14 causes the application of current to the field winding 54 of motor 12. This is effected by a lost motion like 56 connecting teeth 41 to field switch 58. Switch 58, as shown in FIG. 2, is located in an opening 60 of an axially extending wall 62 of drive housing 36. Lost motion linkage 56 includes a rod 64, one end of which is slidably cammed in a curved slot 66 through tooth 41 and the other end of which is connected to a pivoted lever 68, another part of the linkage, that pushes armature 70 of field switch 58. Contacts 72 of switch 58 are held in a normally open position by a spring 74, and upon the alignment of teeth 41 and 42 with flanges 43 and 44, are closed by the linkage to complete the circuit for field winding 54 through switch terminals 75 and 76, brushes 78, commutator bars 80 of rotor 12, brushes 82 and ground 90.

As will be more fully described below with reference to the circuit shown in FIG. 4, the apparatus for detecting the speed of rotor 12 includes output shaft 20 thereof having a tachometer wheel 32 drivably connected. For completing a path for the magnetic flux created by the magnetomotive force (i.e., ampere turns) of actuator coil 14 when energized, tachometer wheel 32 has a plurality of equally spaced teeth 82 extending from the periphery thereof within another plurality of flanges 84 extending from the other end of actuator cylinder 34. The variation of magnetic flux in cylinder 34 caused by the interruption of the flux between teeth 82 and flanges 84 induces a voltage in a tachometer coil 86 that is wound concentrically with actuator coil 14 on a bobbin 88 secured within actuator cylinder 34. To provide a suitable sliding and bearing surface for brake spring 16, a nonmagnetic spring seat 89 is arranged over the hub of tachometer wheel 32 between one end of spring 16 and the axial tips of flanges 84.

OPERATION

The circuit for controlling the energization of actuator coil 14 and the operation of starting motor 10 may be understood with reference to the schematic representation of FIG. 4. As there shown, cranking position contacts 96 of ignition switch 98 connects the positive terminal of battery 102, both to the base of transistor 104 through resistor 106 and to the collector of transistor 104 through actuator coil 14. Since the emitter of transistor 104 is grounded at 90 through diode 108, such closure of cranking contacts 96 turns on transistor 104 to draw current through actuator coil 14. This draws teeth 41 and 42 of actuator armature 38 into alignment with flanges 43 and 44 of actuator cylinder 34 to close contacts 72 of field switch 58 through the action of lost motion linkage 56. Current is then applied through field coil 54 to armature windings of rotor 12 through brushes 78 and 82 and commutator bars 80.

As the speed of rotor 12 increases, the interruption of the flux path between tachometer teeth 82 of wheel 32 and flanges 84 of cylinder 34 varies the flux density therein, thereby inducing voltage pulses in tachometer coil 86. The negative going pulses, and especially that upon the first flux interruption or start up, are blocked by diode 110 and the positive going pulses are applied thereby through resistor 112 to a filter comprised of capacitor 114 in parallel with resistor 116. The voltage

developed by this filter is proportional to the change of flux produced in actuator cylinder 34 by tachometer wheel 32, such change being proportional to the speed of rotor 12.

When the rotor 12 attains a predetermined speed, the voltage developed by the filter is sufficient to enable the gate of SCR 120 through conductor 118. Since the anode of SCR 120 is biased positively with respect to the cathode from battery 102 through cranking contact 96, the enabling voltage on conductor 118 renders SCR 120 conductive, thereby grounding the base of transistor 104 and rendering transistor 104 nonconductive. This opens the current path through actuator coil 14 and allows the return of actuator armature 38 and the opening of field contacts 72, as has been hereinabove described. Diode 108, connected to the emitter of transistor 104 in this circuit, assures that the voltage at the base of transistor 104 when conductive is slightly above ground 90, thereby assuring a forward anode to cathode bias on SCR 120. Diode 123 connected across actuator coil 14 allows the energy therein to dissipate upon deenergization rather than develop voltage transients that could damage transistor 104.

The circuit shown in FIG. 4 also assures that actuator coil 14 and in turn starting motor 10 are not inadvertently activated during normal running of the engine. Such protection is provided through a circuit coupled to the gate of SCR 120 and energized from battery 102 through running contacts 100 of ignition switch 98 and an oil indicator lamp 122. Upon initial closure of ignition switch 98, the path from battery 102 is completed to ground 90 through running contacts 100, oil indicator lamp 122, and the normally closed contacts of an oil pressure switch 124. The increase in oil pressure caused when cranking or running the engine opens the oil pressure switch 124 to provide an otherwise grounded enabling voltage to the gate of SCR 120 from battery 102 through lamp 122, resistor 126, and diode 128. Diode 110 blocks any leakage through this path from battery 102 to ground 90. Should the cranking contacts 96 of ignition switch 98 be inadvertently closed thereafter, SCR 120 would be rendered conductive to prevent conduction through transistor 104 and therefore both energization of actuator coil 14 and in turn activation of the starting motor 10.

Since, before attaining self-sustaining operation, the engine may develop sufficient oil pressure to open oil pressure switch 124, means must be provided to allow continued energization of coil 14, and the cranking resulting therefrom, for some period after the closure of cranking contact 96. Thus, means must be provided to prevent the voltage that would otherwise be grounded through the contacts of oil pressure switch 124 from enabling the gate of SCR 120 through resistor 126 and diode 128 for some period after the closure of cranking contacts 96. To effect such operation, a transistor 130 having its collector connected between resistor 126 and the anode of diode 128 and its emitter connected to ground 90 is rendered conductive to ground the enabling voltage shortly after the closure of cranking contacts 96 and prior to the opening of oil switch contact 124. However, since conduction through transistor 130 promptly upon closure of cranking contacts 96 would defeat the above-described protection against inadvertent starting motor cranking

with the engine running, conduction through transistor 130 is delayed for a period depending on charging characteristics of capacitor 132 and a breakdown voltage of a Zener diode 134 connected with the base of transistor 130, as shown. Thus, capacitor 132 charges from battery 102 through the closed cranking contact 96 and a resistor 136 until Zener 134 breaks down to provide a bias across resistor 138 rendering transistor 130 conductive. 5

Oil pressure switch 124, transistor 130, Zener 134, and capacitor 132 thus cooperate first to lock out attempted energization of coil 14 with the engine running; secondly, to permit such lockout for only a short period after the commencement of such attempted energization with the engine running; and thirdly, to prevent such energization with the engine running after the short period in order to permit the engine to be started in the first place. The period of lockout is selected on one hand to be longer than the period of any inadvertent or accidental closure of the cranking contacts 96 but substantially shorter on the other hand than the shortest contemplated period required for engine starting. 10 15 20

As a further protective feature, possible damage to the internal gear train by attempted re-engagement with the rotor 12 not stopped is provided promptly upon the deenergization of actuator coil 14 through the action of spring 16 urging rotor 12 against break washer 18. Thus, rotor 12 would be braked after the opening of cranking contacts 96 upon an apparent engine start, and damage would be avoided upon subsequent closure of contact 96 to reinstitute cranking when the non-start condition becomes apparent. 25 30 35

Having described one embodiment of the present invention, it is understood that the specific terms and examples are employed in a descriptive sense only and not for the purposes of limitation. Other embodiments of the invention, modifications thereof, and alternatives thereto may be used. We therefore aim in the appended claims to cover such modifications and changes as fall within the true spirit of my invention. 40

What we claim is new and desire to secure by Letters Patent of the United States is:

1. In a starting mechanism having a translatable output shaft, means for detecting the speed of said shaft and translating said shaft comprising in combination:

- a. a first magnetically susceptible member supported about said shaft and comprising a flange; 50
- b. first coil means electrically energizable to establish a magnetic flux in said shaft for translating said shaft;
- c. a second magnetically susceptible member rotatable with said shaft in proximity to said flange of said first member, whereby with said first coil means energized a magnetic flux path is provided through said first and second members and said shaft and whereby the density of said magnetic flux between said second member and said flange varies with the rotation of said second member relative to said first member; and
- d. second coil means operative to develop signals of magnitude and frequency varying with said said flux density, whereby said signals represent the speed of said shaft. 60 65

2. In a starting mechanism having a shaft, a housing rotatably supporting said shaft, and a housing part rotatable about said shaft, means for detecting the speed of said shaft and rotating said housing part thereabout comprising in combination:

- a. a first magnetically susceptible member supported by said housing about said shaft and comprising a flange;
- b. first coil means electrically energizable to establish a magnetic flux in said shaft;
- c. a second magnetically susceptible member rotatable with said shaft in proximity to said flange of said first member, whereby with said first coil means energized a magnetic flux path is provided through said first and second members and said shaft and whereby the density of said magnetic flux between said second member and said flange varies with the rotation of said second member relative to said first member;
- d. second coil means operative to develop signals of magnitude and frequency varying with said change in said flux density, whereby said signals represent the speed of said shaft;
- e. a third magnetically susceptible member having a tooth displaceable between aligned and non-aligned positions relative to a second flange of said first member, whereby said first, second, and third members and said shaft provide a path for said magnetic field created by said energization of said first coil means; and
- f. means connecting said third member and said housing part, whereby said third member rotates said housing part about said shaft when said first coil means are energized and said tooth of said third member rotates from said nonaligned to said aligned positions.

3. In a starting mechanism having a shaft, a housing rotatably supporting said shaft, and a housing part rotatable about said shaft, means for detecting the speed of said shaft and rotating said housing part thereabout comprising in combination:

- a. a first magnetically susceptible member supported by said housing about said shaft and comprising a flange;
- b. first coil means electrically energizable to establish a magnetic flux in said shaft;
- c. a second magnetically susceptible member rotatable with said shaft in proximity to said flange of said first member, whereby with said first coil means energized a magnetic flux path is provided through said first and second members and said shaft and whereby the density of said magnetic flux between said second member and said flange varies with the rotation of said second member relative to said first member;
- d. second coil means operative to develop signals of magnitude and frequency varying with said change in said flux density, whereby said signals represent the speed of said shaft;
- e. a third magnetically susceptible member rotatable relative to said shaft and said first member, said third member having a tooth in a position of alignment with a second flange of said first member when said first coil means are energized and in a position of non-alignment when said first coil

- means are deenergized, whereby said first, second and third member and said shaft provide a path for magnetic flux created by the energization of said first coil means;
- f. first and second drive means, said first drive means drivably connected with said shaft and said second drive means drivably connected with said first drive means and supported by said housing part; and
- g. resilient means connecting said second member and said housing part, whereby rotation of said third member to one of said aligned and non-aligned positions rotates said second drive means about said first drive means.
4. In a starting mechanism having a shaft, a housing rotatably supporting said shaft, and a housing part rotatable about said shaft, means for detecting the speed of said shaft and rotating said housing part thereabout comprising in combination:
- a. a first magnetically susceptible member supported by said housing about said shaft and comprising a flange;
  - b. first coil means supported electrically energizable to establish a magnetic flux in said shaft;
  - c. a second magnetically susceptible member rotatable with said shaft in proximity to said flange of said first member, whereby said first coil means energized a magnetic flux path is provided through said first and second members and said shaft and whereby the density of said magnetic flux between said second member and said flange varies with the rotation of said second member relative to said first member;
  - d. a third magnetically susceptible member rotatable relative to said shaft and to said first member, said third member having a tooth displaceable between an aligned and a non-aligned position relative to a second flange of said first member, whereby said first, second and third members and said shaft provide a path for said magnetic field created by said energization of said first coil means;
  - e. means connecting said third member and said housing part, whereby said third member rotates said housing part when said first coil means are energized and said tooth of said third member is in one of said aligned and non-aligned positions with respect to said second flange of said first member; and
  - g. second resilient means connecting said first and second members and operative when said coil means are deenergized to return said second member into said position of non-alignment with respect to said first member.
5. In a starting mechanism having an output shaft, first, second, and third normally non-conductive switches each having an input and an output electrode, a normally conductive switch responsive to and opened by the presence of a predetermined external condition, said normally conductive switch being connected with said output electrode of said first normally non-conductive switch, a battery having a first terminal connected to a point of constant reference potential and a second terminal connected to said input electrode of said first, second, and third normally non-conductive switches, an improved circuit for controlling said mechanism comprising:

- a. a first magnetically susceptible member displaceable relative to said third normally non-conductive switch and operable when displaced relative thereto to switch said third switch between a conductive state and a non-conductive state;
- b. a second magnetically susceptible member for providing magnetic flux to said first member to displace said first member relative to said third switch;
- c. a third magnetically susceptible member operable to change said magnetic flux in said second member in response to the speed of said shaft, whereby said change in flux in said second member varies with said speed;
- d. a first transistor having an output electrode connected to said point of constant reference potential and a control electrode connected to said output electrode of said second switch;
- e. a second transistor having an input electrode connected to said output electrode of said first switch, an output electrode connected to said point of constant reference potential, and a control electrode connected to said output electrode of said second switch;
- f. first coil means for creating said magnetic flux, said first coil means having one end thereof connected to said output electrode of said second switch and the other end thereof connected to said input electrode of said first transistor, whereby, when said second switch is rendered conductive, said first transistor is rendered conductive to energize said first coil means and whereby said flux displaces said first member relative to said second member to render said third switch conductive;
- g. a controllable unidirectional current conducting device having an anode connected with said output electrode of said second switch, a cathode connected with said point of constant reference potential, and a control electrode connected with said output electrode of said first switch, said device being rendered conductive upon the application of a predetermined voltage to the control electrode thereof, whereby when said device is conductive, said first transistor is rendered non-conductive to deenergize said first coil means, thereby allowing said first magnetically susceptible member to be displaced relative to said second magnetically susceptible member to render said third switch non-conductive; and
- h. second coil means responsive to said change in magnetic flux effected in said second magnetically susceptible member, one end of said second coil means being connected to said point of constant reference potential and the other end connected to said control electrode of said controllable unidirectional current conducting device, whereby when said shaft exceeds a predetermined speed, said second coil means produce said predetermined voltage.
6. In a starting mechanism having an output shaft, first, second, and third normally non-conductive switches each having an input and an output electrode, a normally conductive switch responsive to and opened by the presence of a predetermined external condition, said normally conductive switch being connected with said output electrode of said first normally non-con-

ductive switch, a battery having a first terminal connected to a point of constant reference potential and a second terminal connected to said input electrode of said first, second, and third normally non-conductive switches, an improved circuit for controlling said mechanism comprising:

- a. a first magnetically susceptible member displaceable relative to said third normally non-conductive switch and operable when displaced relative thereto to switch said third switch between a conductive state and a non-conductive state;
- b. a second magnetically susceptible member for providing magnetic flux to said first member to displace said first member relative to said third switch;
- c. a third magnetically susceptible member operable to change said magnetic flux in said second member in response to the speed of said shaft, whereby said change in flux in said second member varies with said speed;
- d. a first transistor having an output electrode connected to said point of constant reference potential and a control electrode connected to said output electrode of said second switch;
- e. a second transistor having an input electrode connected to said output electrode of said first switch, an output electrode connected to said point of constant reference potential, and a control electrode connected to said output electrode of said second switch;
- f. first coil means for creating said magnetic flux, said first coil means having one end thereof connected to said output electrode of said second switch and the other end thereof connected to said input electrode of said first transistor, whereby, when said second switch is rendered conductive, said first transistor is rendered conductive to energize said first coil means and whereby said flux displaces said first member relative to said second member to render said third switch conductive;
- g. a controllable unidirectional current conducting device having an anode connected with said output electrode of said second switch, a cathode connected with said point of constant reference potential, and a control electrode connected with said output electrode of said first switch, said device being rendered conductive upon the application of a predetermined voltage to the control electrode thereof, whereby when said device is conductive, said first transistor is rendered non-conductive to deenergize said first coil means, thereby allowing said first magnetically susceptible member to be displaced relative to said second magnetically susceptible member to render said third switch non-conductive;
- h. second coil means responsive to said change in magnetic flux effected in said second magnetically susceptible member, one end of said second coil means being connected to said point of constant reference potential and the other end connected to said control electrode of said controllable unidirectional current conducting device, whereby when said shaft exceeds a predetermined speed, said second coil means produce said predetermined voltage; and

- i. a unidirectional current conducting device having an anode connected to said input electrode of said second transistor and a cathode connected to said control electrode of said controllable unidirectional current conducting device, whereby with said first and second switches conductive, said controllable unidirectional current conducting device may be rendered conductive with one of said predetermined voltage and conduction through said second switch after said normally conductive switch is rendered non-conductive.
- 7. In a starting mechanism having a translatable output shaft, means for detecting the speed of said shaft and for operating a brake by translating said shaft comprising in combination:
  - a. a first magnetically susceptible member supported about said shaft and comprising a flange;
  - b. first coil means electrically energizable to establish a magnetic flux in said shaft for translating said shaft and operating said brake;
  - c. a second magnetically susceptible member rotatable with said shaft in proximity to said flange of said first member, whereby with said first coil means energized a magnetic flux path is provided through said first and second members and said shaft and whereby the density of said magnetic flux between said second member and said flange varies with the rotation of said second member relative to said first member; and
  - d. second coil means operative to develop signals of magnitude and frequency varying with said change in flux density, whereby said signals represent the speed of said shaft.
- 8. A cranking mechanism for an internal combustion engine comprising:
  - a. an electric cranking motor having an output shaft, a rotor mounted on said shaft, and a stator electrically energizable to rotate said rotor;
  - b. an actuator winding telescoped over said shaft and effective when energized to provide a magnetic field having a flux path linking said shaft;
  - c. a toothed wheel rotatable with said shaft and forming a part of the magnetic circuit encircling said actuator winding, whereby an alternating component of magnetic flux is developed in accordance with the shaft rotational velocity;
  - d. a pickup winding encircling the flux path of said alternating component;
  - e. circuit means responsive to the emf of said actuator winding and effective to interrupt the current supplied thereto when said emf reaches a predetermined frequency;
  - f. an actuator cylinder supported about said shaft and comprising a flange, said actuator member forming a part of the flux path of said actuator coil;
  - g. an armature member forming a part of the flux path of said actuator winding and circumferentially rotatable about said shaft between aligned and non-aligned positions relative to said flange when said actuator winding is respectively energized and de-energized;
  - h. spring means biasing said armature member towards said non-aligned position; and
  - i. switch means responsive to the motion of said armature member to said aligned position defining an energizing circuit to the cranking motor.
